UNITED STATES PATENT OFFICE.

NOYES F. PALMER, OF BROOKLYN, NEW YORK.

DESIGN FOR A FOUNTAIN-PEN NOZZLE.

SPECIFICATION forming part of Design No. 19,265, dated August 13, 1889.

Application filed June 26, 1889. Serial No. 315,641. Term of patent 14 years.

To all whom it may concern:

Be it known that I, NOYES F. PALMER, of Brooklyn, New York, have invented and produced a new and original Design for a Fountain-Pen Nozzle, of which the following is a specification, reference being had to the accompanying drawings, forming part thereof.

Figure 1 is a side elevation of my newly-designed fountain-pen nozzle. Fig. 2 is a section on line 2 2, Fig. 1.

The leading feature of my design consists of a cylindrical tube, which runs out into a tongue at one end and has a threaded extension at the other end, and of a milled knurl 15 of convex outline surrounding the tube in front of the threaded extension.

A is a cylindrical tube running out in front in a tongue c, and having at its rear end a threaded extension a. Forward of this extension the tube A is surrounded by an an-

nular knurl or projection b. This knurl has straight ends b' at right angles to the tube. The periphery of the knurl between the ends b' is arc-shaped in cross-section—that is to say, it is highest at the center and tapers 25 toward the ends b'. The surface of the arched periphery is milled by obliquely-set ridges and grooves.

I claim as my design—

The design for a fountain-pen nozzle, consisting of a cylindrical tube A, having a forwardly-projecting tongue c and a threaded extension a, and of a convex knurl b, surrounding tube A in front of the threaded extension and having a milled periphery, substantially as shown.

NOYES F. PALMER.
